UNITED STATES PATENT OFFICE.

EDWIN H. BELL, OF CHICAGO, ILLINOIS.

TIE-PLATE.

No. 905,493.

Specification of Letters Patent.

Patented Dec. 1, 1908.

Application filed June 13, 1907. Serial No. 279,680.

To all whom it may concern:

Be it known that I, EDWIN H. BELL, a citizen of the United States, and a resident of Chicago, in the county of Cook and State 5 of Illinois, have invented certain new and useful Improvements in Tie-Plates; and I do hereby declare that the following is a full, clear, and exact description thereof, reference being had to the accompanying 10 drawings, and to the letters of reference marked thereon, which form a part of this specification.

This invention relates to improvements in railway tie-plates such as applied between 15 railroad rails and the supporting ties in order to prevent the wearing away of the ties and to aid in securing the rails firmly to the ties.

The invention relates more especially to 20 that class of tie-plates having longitudinal ribs or flanges on their under surfaces which penetrate the wood of the tie and have transverse shoulders on their upper surfaces against which bear the outer edges of the 25 base flanges of the rails to hold the rails from spreading or moving outwardly.

The invention consists in the matters 30 hereinafter set forth and pointed out in the appended claim.

As illustrated in the accompanying drawings:—Figure 1 is a perspective view of a tie-plate embodying one form of my invention. Fig. 2 is a plan view of the tie-plate shown in Fig. 1. Fig. 3 is a sectional view 35 taken longitudinally of the tie-plate and transversely through the rail showing the base-flange of the rail and a part of the tie. Fig. 4 is a cross-section of the tie-plate, taken upon line 4—4 of Fig. 2. Fig. 5 is a 40 sectional view like Fig. 4, showing the tie-plate before the spike-holes are punched therein. Fig. 6 is a view of a tie-plate generally like that shown in Figs. 1 to 5, the same being a narrower tie-plate with four 45 flanges thereon.

Referring to the form of tie-plate shown in Figs. 1 to 5, inclusive. A indicates the horizontal body portion of the tie-plate, A¹ A¹ two marginal depending parallel flanges 50 thereon, and A² A² A² are depending flanges located between the marginal flanges A¹ A¹. All of said flanges are downwardly tapered or wedge-shaped in order to facilitate their 55 being driven into the tie. The top surface of the tie-plate is shown as provided with longitudinal grooves a a arranged parallel

with each other above the several flanges A¹ A². Said grooves form a series of parallel, elevated bearing surfaces for contact with the rail and serve to decrease the weight of the plate without materially affecting its strength or stiffness. B indicates a transverse rib extending across the tie-plate near one of its ends and having a vertical inner face which forms a shoulder for contact 60 with the base-flange of the rail and serves to prevent outward movement or shifting of the rail upon the tie-plate. The tie-plate shown in said Figs. 1 to 5 is provided with four spike-holes C C C C located near the 65 ends of the plate and extending through the body thereof between the marginal flanges A¹ A¹ and the next adjacent inner flanges A² A². The spike-holes C C are located at the end of the plate adjacent to the rib B 70 and are cut through said rib; the inner margins of the said spike-holes being located slightly inside of the plane of the inner vertical face or shoulder of the said rib so that spikes driven therethrough may properly engage the edge of the base-flange of the rail when the latter is in contact with said shoulder. Said rib B is of different height in its 75 different parts and is made of less height in its parts through which the spike-holes extend than elsewhere. In the form of plate shown in said Figs. 1 to 5, in which the spike-holes C C are located adjacent to the side margins of the plate, the rib B is made 80 considerably higher in its middle part between the spike-holes than at its end portions at which the said spike-holes are located.

In the form of tie-plate shown, which is made by a rolling operation, the rib B has the form of a plurality of upwardly rounded projections, the highest parts of which are located on the portions of the tie-plate between the grooves a a, the elevated portions being joined with each other to form a continuous rib, and said rib consists of two higher rounded projections b b located between the spike-holes C C, and the two lower projections b' b' adjacent to the side margins of the plate, through which said spike-holes 90 C C are formed. The form of the rib B, 95 before the spike-holes are cut or punched in the plate, is illustrated in Fig. 5.

The higher projections b b are substantially higher than the thickness of the edge 100 of the base-flange of the rail which rests in contact with the shoulder formed by the rib,

while the lower parts b^1 of the rib are not higher than the thickness of said edge of the base-flange. The higher portions b^2 of the rib afford a relatively deep shoulder having ample bearing surface for the base-flange of the rail, while the lower portions $b^1 b^1$ of the rib have their upper edges not higher than the level of the tops of the rail base-flange, so that the projecting sides of the spike-heads will not strike the same when the spikes are driven in to bring the heads thereon into close contact with the said base-flange. In other words, the lower parts of the rib, while being continuous with the higher parts and forming therewith a rib extending substantially across the entire width of the plate, and affording a shoulder having ample bearing surface to receive the outward pressure of the rail, are at the same time so arranged that they will not interfere with the engagement of the spike-heads with the base-flange of the rail when the spikes are driven. This feature is clearly illustrated in Fig. 3, wherein D indicates the tie, E the base-flange of the rail and F a spike which is driven through the spike-hole with the head in contact with the top of the base-flange E.

Fig. 6 shows a narrower tie-plate G having two marginal, longitudinal depending flanges $G^1 G^1$ and two intermediate flanges $G^2 G^2$, and a transverse rib H having higher and lower parts arranged reversely to those of the rib shown in Figs. 1 to 5. Said tie-plate G has three spike-holes I I¹ I¹ one of which, I, is located centrally of the end of the plate in line with the rib H, and the said rib has two rounded, elevated portions $h^1 h^1$ adjacent to the side margins of the plate and an intermediate, lower portion h^2 through which extends the spike-hole I.

A rolled metal tie-plate having flanges on its lower surface, grooves in its upper surface in line with the flanges, and a transverse rib on its upper surface to form a rail-abutting shoulder, said rib consisting of a plurality of upwardly rounded projections separated from each other by depressed portions corresponding in location with said grooves, which projections are of unequal height, has the advantage that the higher projections may be made to extend a distance above the upper face of the plate sufficient to afford a shoulder of ample vertical depth to give a reliable bearing surface for the edge of the rail base-flange, while at the same time such a rib with rounded projections may be easily formed on the

plate in the operation of rolling. The metal which forms said transverse rib, as a whole, is obtained in the rolling operation by displacement endwise of the metal of the plate, while the metal to form the higher projections is displaced laterally of the plate, or endwise of the rib, the lower connecting parts of the rib, by which the same is made continuous, permitting such lateral displacement of the metal. In other words, in the rolling operation sufficient metal is displaced endwise of the plate to make the rib, as a whole, while the extra quantity of metal required to form the higher rounded projections is derived by lateral displacement of the metal from the parts of the rib having the lower projections and at which the metal is depressed between the projections. 75

I am aware that tie-plates have been heretofore made of malleable cast metal, having a rib which is higher in some parts than in others; the essential feature of novelty in the tie-plates hereinbefore described consisting in a rolled metal tie-plate flanged on its lower, and grooved on its upper, surface and having a transverse rib formed by rounded projections of unequal height, joined to each other by depressed parts so that the rib is, in effect, continuous and metal is furnished to form the higher rounded projection by displacement of the metal longitudinally of the rib both from the parts of the rib at which the lower projections are located and the parts of the rib which are depressed between the projections. 80

I claim as my invention:—

A tie-plate provided on its under surface with a plurality of depending, parallel flanges, and on its top surface with a plurality of grooves located severally above and parallel with said flanges, said plate being provided with a transverse rib forming a rail-abutting shoulder, said rib consisting of a plurality of upwardly rounded projections of unequal height, severally located between said grooves and separated by depressions in the rib corresponding in location with the said grooves. 95

In testimony, that I claim the foregoing as my invention I affix my signature in the presence of two witnesses, this 3rd day of June A. D. 1907. 100

EDWIN H. BELL.
